WAVE SIGNALING SYSTEM

John F. Farrington, Flushing, N. Y., assignor to
Hazeltine Corporation, a corporation of Delaware

Application April 18, 1935, Serial No. 16,949

25 Claims. (CL. 250—20)

My invention relates to wave-signaling systems, and more particularly to such systems including provisions for reducing the effect of transient electrical disturbances, while at the same time favoring the transmission or reception of desired signal waves.

In the use of wave-signaling receivers of either the space-radiation or wired type, considerable difficulty is often experienced from electrical disturbances or transient pulses of considerable magnitude originating external to the receiver and transmitted to the input terminals thereof along with the signal waves. Such transients may be of natural origin, as lightning discharges, or the like, associated with local thunderstorms or atmospheric disturbances; or such transients may be of artificial origin arising from arcing at leaky insulation points on power transmission lines, from sparking at motors, switches or sliding contactors of electric railways, household or factory electrical equipment, or the like, or from ignition systems of internal combustion engines or other well known sources too numerous to recite.

Such electrical disturbances are usually induced directly on the receiving antenna of a space-radiation system or upon the transmission conductors of a wire system, and, although usually transient in character and of short individual duration, the proximity of their source to the receiver may result in very large amplitudes of such disturbances relative to the intensity of the desired signal. This is particularly true when such a receiver is utilized for receiving waves of widely different intensity, as from remote and local stations. Electrical disturbances, such as previously mentioned, may be regarded as possessing component waves of frequencies to which the receiver is tuned. Therefore the selective circuits of the receiver pass these waves to the final detector where they are converted to audio frequency waves which pass through the audio circuits and appear as noise in the output in direct competition with the desired signaling waves. The intelligibility of the signals and, in the case of broadcast entertainment programs, the enjoyment value as well, thus are impaired. If the noise is very much stronger than the signal, even though intermittent in character, reception of the signal becomes well-nigh impossible.

While arrangements have previously been devised for automatically controlling the amplification of a signal-translating or receiving system to compensate for changes in intensity of the

received signal waves, such arrangements have necessarily had a time constant sufficiently high to prevent their following the modulation envelope of the signal carrier-wave and, hence, have not ordinarily been sufficiently rapid in their operation to reduce the transmission or reproduction of such transient electrical pulses of short duration.

It is an object of my invention, therefore, to provide a wave signal-translating or receiving circuit which shall be substantially free from the undesirable characteristics described above and which will provide satisfactory signal translation or reproduction even in the presence of disturbing electrical transients.

It is another object of my invention to provide an improved wave signal-translating or receiving system by means of which electrical transients or pulses received at the input circuit of the system and of comparatively large amplitude relative to the desired signal are substantially suppressed.

It is a further object of my invention to provide an improved wave signal-translating or receiving circuit in which there is included provision for rendering the signal channel substantially inoperative during intervals when the magnitude of an electrical disturbance transmitted thereto exceeds by an appreciable amount a predetermined relationship to the desired signal.

It is a still further object of my invention to provide an improved signal-translating or reproducing system subject to the reception of signals of variable intensity including provisions for controlling the amplification characteristics of the system to compensate for such variations in intensity of received signals and for maintaining the signal at the most favorable level to effect a suppression of disturbing electrical transients.

While my invention is of general application, it is described hereinafter as embodied in a radio broadcast receiver including conventional modulated carrier-wave selecting, amplifying, and signal-detecting circuits followed by a signal-frequency amplifier. In accordance with my invention, a vacuum tube or tubes of one or more of the translation stages of the system is provided with a control electrode which, for normal or maximum signal strengths, is biased at or near the point of the tube characteristic beyond which the amplification of the tube is sharply reduced. A biasing voltage is derived by rectifying input waves either by certain of the active electrodes of the tubes of the system or by auxiliary elec-

trodes or tubes, and this biasing voltage is applied to the control electrode of a noise-controlling tube. The normal bias of this control electrode may consist solely of a fixed bias voltage or a fixed bias plus the rectified voltage just described. In either case the total biasing voltage corresponding to maximum signal strength is just short of providing a cutoff of the noise controlling tube. If the total input to the system; that is, the signal plus the disturbing electrical transients as translated or amplified by the system, substantially exceeds the normal maximum signal input to the rectifying means, a voltage derived from the signal wave by rectification, as described, and impressed upon the control electrode is effective to bias the control electrode of the tube to cut off and substantially suppress—not limit—the transfer of the signal and/or noise through the system; that is, to reduce the signal-translation efficiency of the system to a very low value. In case the biasing voltage of the control tube consists solely of a fixed bias voltage, no additional rectified voltage is added thereto until the total input to the system exceeds the normal signal intensity.

The time constant of the biasing control circuit just described is preferably sufficiently small to avoid unnecessary lengthening of the duration of "blank" spaces in the chain of reproduced signals, or the program, beyond the interval actually occupied by the undesired electrical disturbances.

In accordance with a further feature of my invention a system as described above is provided with an automatic amplification control arrangement for maintaining the desired signal input to the noise suppressor substantially constant, irrespective of the amplitude of the incoming carrier wave, to enable the system to operate with a most favorable ratio of signal amplitude to that of the disturbing electrical transients.

For a better understanding of my invention, together with other and further objects and features thereof, reference is had to the following description taken in connection with the accompanying drawings, and its scope will be pointed out in the accompanying claims.

Fig. 1 is a schematic diagram of a complete radio broadcast receiver of the superheterodyne type including a schematic representation of a circuit for suppressing electrical disturbances in accordance with my invention; Fig. 2 is a detailed circuit diagram of one circuit arrangement for suppressing electrical disturbances shown schematically in Fig. 1; Fig. 3 is a detailed circuit diagram of a modified form of the system of Fig. 2; while Fig. 4 is a circuit diagram similar to Fig. 3 but modified to provide an output circuit employing only a single tube.

Referring now more particularly to Fig. 1 of the drawings, there is schematically shown a superheterodyne type of radio broadcast receiver embodying my invention in which radio-frequency signal-modulated waves are intercepted by an antenna 10 and supplied to a radio-frequency selector and amplifier 14, the antenna circuit being completed by a ground connection 12. The output of the radio-frequency selector and amplifier 14 is impressed upon the input of an oscillator-modulator 16 by means of which the radio-frequency currents are converted into signal-modulated intermediate-frequency waves. The intermediate-frequency waves are further amplified by an intermediate-frequency amplifier 18 and impressed upon the input of

a second detector which is included in a unit 20. The unit 20 includes also a conventional arrangement for deriving a unidirectional voltage variable in accordance with the average amplitude of the received carrier wave and may include, further, any desired number of audio-frequency amplifying stages. The unidirectional voltage developed by the unit 20 may be applied, as indicated, to the radio-frequency amplifier 14, oscillator-modulator 16, and intermediate-frequency amplifier 18 automatically to control the amplification of these devices to maintain the signal output of the unit 20 within predetermined limits, as is well understood in the art. While such an automatic volume control is effective to maintain the signal output of the unit 20 within predetermined limits, irrespective of the variations in intensity of the received carrier waves, such a control does not effect an exact levelling of the signal. The audio-frequency currents developed in the unit 20 are transferred through transformer 24 to the terminals A and B of the noise interference reduction circuit 22. The noise interference reduction circuit which constitutes the present invention will be described more particularly hereinafter. The output terminals A', B' of the noise-interference reduction circuit 22 are connected to the power amplifier 26 by which the audio-frequency signals are further amplified and transmitted to the sound reproducer or loudspeaker 28.

The various portions of the receiver shown in Fig. 1, with the exception of the noise-interference reduction circuit 22, may be of conventional type and, since they constitute no part of the present invention, a further description thereof is deemed unnecessary.

Referring, now, to Fig. 2, there is illustrated a preferred embodiment of the noise-interference reduction circuit indicated at 22 in Fig. 1. The terminals, A, B, X, A' and B' correspond with similarly indicated terminals in Figs. 1. Essentially, this circuit consists of a two-stage audio-frequency amplifier comprising a first vacuum tube VT₁ having an input electrode connected to the input circuit AB through a manual volume adjusting potentiometer P₁ and coupled through a transformer T₁ to a pair of vacuum tubes VT₂ and VT₃ connected in push-pull relation. The output circuit of the push-pull amplifier comprising tubes VT₂ and VT₃ is coupled to the output terminals A', B' through a transformer T₂ and a second manually adjustable volume control potentiometer P₂. The tube VT₁ may be of any suitable type, though I have shown a pentode, in which case the amplification control bias from the terminal X may be impressed upon the outer or suppressor grid through a resistance R₅ and filtering condenser C₄ which have a time constant of sufficient magnitude to prevent their following the ordinary variations of signal intensity at the modulation frequency and yet sufficiently small to permit control of the amplification of the tube VT₁ without undue time lag. Biasing resistors R₂, R₃ and R₄ may be included in the cathode circuit of the tube VT₁ in conjunction with audio-frequency by-pass condenser C₂. A suitable biasing voltage for the signal input electrode may be derived from these resistors, as shown.

The second stage of the noise-reducing circuit comprises a unique form of push-pull amplifier, including vacuum tubes VT₂ and VT₃. Again, these tubes may be of any suitable type, but when of the pentode type, as shown, the input circuit

comprising the secondary winding of the transformer T_1 may be connected to their inner control electrodes. This winding is mid-tapped in a conventional manner and connected to ground through a circuit comprising a resistance R and a condenser C in parallel and proportioned as described in more detail hereinafter. A resistance R_7 may be connected across the secondary winding of T_1 to obtain a substantially flat frequency-gain characteristic within the operating limits of the circuit. The control of the tubes VT_2 and VT_3 for the reduction of the interfering electrical disturbances may be effected through the outer or suppressor grids, which are connected to ground through the circuit $R-C$. Positive voltages for the tubes VT_1 , VT_2 and VT_3 may be supplied from any suitable source, indicated as $+B$, through resistors R_1 and R_5 , respectively, shunted by audio-frequency by-passing condensers C_1 and C_3 , respectively. A bleeder resistance R_6 may be connected between the cathodes of the tubes VT_2 and VT_3 and the mid-point of the primary winding of output transformer T_2 for the purpose of maintaining supply voltages to the tubes substantially independent of the anode current of the push-pull amplifier.

Disregarding the circuit $R-C$ for the moment and assuming suitable bias voltages to be supplied to the control and suppressor grids of the tubes VT_2 and VT_3 , the above-described circuit operates as a conventional two-stage audio-frequency amplifier in which variations in the intensity of the signal translated through the amplifier circuit, due to variations in intensity of the received carrier wave, are minimized by the amplification control bias applied through the terminal X to the tube VT_1 of the first stage. It will be noted, however, that the cathodes of the tubes VT_2 and VT_3 are connected to ground through the biasing resistor R_4 so that the signal input grids of these tubes are normally maintained at negative voltage, with respect to their cathodes, by the amount of the voltage across the resistance R_4 . The values of resistances R_2 , R_3 and R_4 are so chosen that the magnitude of the bias voltage across resistor R_4 is greater than the maximum value of the signal input to the tubes VT_2 and VT_3 under normal operating conditions. With such an arrangement the signal input electrodes of the tubes VT_2 and VT_3 are maintained continuously negative so that no grid currents flow in their respective circuits.

Upon the occurrence of an electrical transient or disturbance of considerable magnitude relative to the desired signal, the instantaneous amplitude of the voltage input to the inner or signal grids of the tubes VT_2 and VT_3 becomes greater than the bias voltage of the resistor R_4 with the result that a rectified current flows in the circuit RC , developing a bias voltage across resistor R which is impressed upon the outer or suppressor grids of the tubes VT_2 and VT_3 , which may be termed the control electrodes. The normal biasing voltages of the several control electrodes of the tubes VT_2 and VT_3 are so selected that these tubes are normally and constantly efficient in the transfer of received signals but operate near their cutoff value for normal maximum signal intensity. Therefore, any increase in the bias voltage impressed upon the control electrodes of the tubes VT_2 and VT_3 operates instantaneously to cut off these tubes or to reduce materially their amplification and, thus, substantially to reduce the signal-translation efficiency of the circuit and to suppress not only the electrical transient

or disturbance but the signal as well. Because of this complete suppression of the signal, it is desirable that the bias on the control electrodes of the tubes VT_2 and VT_3 be dissipated quickly after cessation of the electrical transients or disturbances. To this end the time constant of the circuit RC is made small, and may be, for example, of the order of .001 second. It is also desirable that this time constant shall be sufficiently small to allow the noise suppression control to follow the modulation envelope to ensure rapid response to audio-frequency disturbances. In certain instances the condenser C may be completely omitted without impairing the operation of the circuit.

It is desirable that full wave rectification of the input wave shall take place in order that a control voltage shall be available to block out noise, regardless of its polarity. The use of the push-pull amplifier circuit also prevents generation of an appreciable voltage wave in the secondary winding of the transformer T_2 due to cutting off of the anode currents by the noise suppression control.

The suppression of the disturbing electrical transients is most effective when the amplitude of the normal maximum signal is held only slightly less than the magnitude of the bias voltage across the resistor R_4 , that is, the bias of the signal input grids of the tubes VT_2 and VT_3 , this relation corresponding to a maximum ratio of signal to disturbing transient. Therefore, it is important that changes in the amplitude of the incoming modulated carrier wave impressed on the receiver shall not produce appreciable change in the amplitude of the signal applied to the grids of noise suppressor tubes. By the application of the automatic amplification control bias through the terminal X to the control electrodes of the tube VT_1 , the levelling of the signal intensity normally accomplished in the radio-frequency portion of the receiver is supplemented to minimize variations in signal intensity as applied to the control electrodes of the tubes VT_2 and VT_3 . If the levelling of the signal input to the push-pull stage comprising the tubes VT_2 and VT_3 approaches the ideal; that is, is sufficiently close to constant level for practical purposes, within the normal operating limits of the system, the potentiometer P_1 may be set permanently so that a 100% modulated carrier wave will give the critical input to the control grids of the tubes VT_2 and VT_3 . However, since certain transmitting stations do not continuously maintain 100% modulation, it is desirable to be able to adjust P_1 for a gain dependent upon the percentage modulation of the particular station being received.

In the arrangement of Fig. 2, the electrodes utilized to control the suppression of electrical transients or disturbances are normally biased by a fixed voltage of such magnitude as to operate the tubes in the push-pull stage near the cutoff. No additional biasing voltage is supplied to these control electrodes until the amplitude of the signal input to the tubes VT_2 and VT_3 exceeds the bias across the resistor R_4 , and grid rectification takes place. In the arrangement of Fig. 3, on the other hand, the fixed negative bias applied to the control electrode for suppressing electrical transients is supplemented continuously by an additional biasing voltage varying with the amplitude of the input to the terminals AB and, when the sum of these two bias voltages exceeds a predetermined value, the tubes VT_2 and VT_3 operate to cut off the transmission of a signal.

In the arrangement of Fig. 3 this latter result is effected either by means of an auxiliary rectifying tube or, as shown, by auxiliary electrodes of a duplex amplifying and rectifying tube VT₄ 5 replacing the tube VT₁ of Fig. 2. In this case also the transformer T₁ of Fig. 2 is replaced by transformer T₂ having a tertiary winding connected to the rectifying electrodes of the tube VT₄ in circuit with the resistance R and condenser C across which is developed the supplemental biasing voltage applied to the suppressor grids of the tubes VT₂ and VT₃. With this arrangement the bias of the signal input electrodes of the tubes VT₂ and VT₃ is not critical and they 10 may be connected to any suitable point in the biasing voltage divider R₂, R₃, R₄ in accordance with the desired operating characteristics of the system.

The operation of the apparatus of Fig. 3 is 20 similar to that of Fig. 2 described above, with the exception that the electrical constants of the circuit are so chosen that, under normal operating conditions, the fixed negative bias applied to the suppressor grids of the tubes VT₂ and VT₃ 25 plus the rectified biasing voltage appearing across the resistor R, corresponding to maximum signal input, operates the tubes VT₂ and VT₃ just short of their cutoff point. Under such conditions, the occurrence of electrical transients or 30 disturbances causes an increased rectified bias to appear across the resistor R which, with the fixed negative bias described, operates the tubes VT₂ and VT₃ beyond their cutoff point to suppress the electrical transient.

35 The same factors determine the selection of constants of the resistor R and condenser C and/or the omission of the condenser C, as apply to the circuit of Fig. 2 described above. With the exception that the biasing resistors R₂ and R₃ 40 are in the common cathode circuit of the tubes VT₂ and VT₃ rather than in that of the tube in the first stage, the remainder of the circuit is similar to that of Fig. 2 and its principles of operation are the same.

45 The circuit of Fig. 4 is similar to that of Fig. 3 with the exception that the second stage is modified in such a way as to secure the advantages of a push-pull amplifier in the suppression of electrical transients by means of a single tube VT₅. The screen and anode circuits of the tube VT₅, shown as pentode type, are connected in 50 push-pull relation with the output transformer T₂. A resistor R₄ and condenser C₅ are preferably included in the anode circuit to balance the 55 screen and anode circuits and prevent distortion in the push-pull output circuit. In this case also the biasing voltage effective to suppress electrical transients is applied to the inner control grid of the tube VT₅, which is normally used 60 as a signal input grid, while the signal input circuit from the transformer T₃ is connected to the outer or suppressor grid. The operation is otherwise similar to that of the circuit of Fig. 3.

65 As in the arrangement of Fig. 2, the potentiometer P₁ in the circuits of Fig. 3 and Fig. 4 is ordinarily permanently adjusted so that the maximum signal input is effective to operate the tube or tubes of the final audio-frequency amplifying stage, in which electrical disturbances or 70 transients are suppressed, substantially at the cutoff point, while the manual volume control of the receiver is effected primarily by the potentiometer P₂.

In each of the above arrangements it is preferable, for best operation of the transient sup-

pression circuit, that no limiting action on the transients or noise pulses shall occur at the receiver preceding the push-pull amplifier in which the control is effected. The transformer ratios, the operating voltages on the several electrodes of the tubes, and the signal input amplitude are 5 preferably suitably chosen with this point in mind.

While my invention has been described as embodied in a circuit arrangement utilizing particular types of tubes with particular arrangements and connections of control electrodes, it is to be emphasized that these particular arrangements of tubes and electrodes are of no material significance and that any equivalent 10 tubes, either single or duplex, or any equivalent electrode connection may be employed in the practice of my invention. Furthermore, while the biasing voltages applied to the control electrodes, to determine the operating characteristics 15 of their associated tubes and circuits and to limit the grid rectification in the circuit of Fig. 2, are shown as being derived from biasing resistors in the space current paths of the tubes, it will be apparent that these voltages may be derived 20 from batteries or any other suitable source of direct voltages. Also, while my invention has been described as applied to the audio-frequency portion of a radio receiver, it is obvious that it 25 may be used in connection with the radio-frequency or intermediate-frequency portions of such a receiver by choosing appropriate values for the circuit elements. Similarly, it may be applied to signal-translating systems forming a 30 portion of a wire communication system operating at either audio or carrier frequencies for the reception or transmission of wave signals.

While I have described what I at present consider the preferred embodiments of my invention, it will be obvious to those skilled in the art that 40 various changes and modifications may be made therein without departing from my invention, and I, therefore, aim in the appended claims to cover all such changes and modifications as fall 45 within the true spirit and scope of my invention.

What is claimed is:

1. In a wave-signaling system, a signal-translating stage having signal input and output circuits and normally efficient in the translation of input signals, means for controlling the amplitude of the desired signal input thereto to maintain the maximum amplitude thereof near and below a predetermined critical value, rectifier means coupled to said input circuit and having a time constant such that it follows substantially 50 instantaneous variations in amplitude of the input current, a source of biasing voltage connected in circuit with said rectifier means in opposition to the rectified voltage developed thereby, whereby rectification takes place only when the 55 amplitude of the input current exceeds said predetermined value, and means for reducing the efficiency of said signal-translating stage in response to the output of said rectifier means.

2. In a wave-signaling system, a signal-translating stage having signal input and output circuits and including a vacuum tube having a plurality of electrodes, means for controlling the amplitude of the desired signal input thereto to maintain the maximum amplitude thereof near 70 and below a predetermined critical value, and means coupled to said input circuit for deriving therefrom a biasing voltage variable with the total current in said input circuit and for applying the same to an electrode of said tube, said 75

means having a time constant such that said biasing voltage is responsive to the instantaneous amplitude above said predetermined value of the input current.

3. In a wave-signaling system, a signal-translating stage having signal input and output circuits and including a vacuum tube having a plurality of electrodes including input and output electrodes, means for controlling the amplitude of the desired signal input thereto to maintain the maximum amplitude thereof near and below a predetermined critical value, said translating stage including rectifier means coupled to said input circuit, a parallel connected resistor and condenser included in the direct-current circuit of said rectifier and having a time constant sufficiently small that the direct voltage thereacross approximately follows the envelope of the signal input to said input circuit, and a circuit for impressing the direct voltage of said rectifier means upon a control electrode of said vacuum tube, the operating voltages of the electrodes of said tube being so related that the gain thereof is substantially reduced only for values of said direct voltage corresponding to amplitudes of input current in excess of said predetermined value.

4. In a wave-signaling system, a signal-translating stage having signal input and output circuits and including a vacuum tube having input and output electrodes and an auxiliary control electrode, sources of operating voltages for said electrodes, said sources being so proportioned that an increase of the operating voltage of said auxiliary electrode beyond its normal value effects a sharp reduction in the gain of the tube, and means comprising a rectifier coupled to said input circuit and including a parallel-connected resistor and capacitor in the direct current path thereof for deriving therefrom a biasing potential and for applying the same to said auxiliary electrode, said means having a time constant such that said biasing potential is dependent upon the instantaneous amplitude of the input current, whereby the translation efficiency of the system is sharply reduced when said instantaneous amplitude exceeds a predetermined value.

5. In a wave-signaling system, a signal-translating stage having signal input and output circuits and including a vacuum tube having input and output electrodes and an auxiliary control electrode, said input electrode being connected to said input circuit, a source of constant bias voltage for said input electrode whereby current flows in its associated circuit only for amplitudes of input voltage exceeding a predetermined value, impedance means in the circuit of said input electrode traversed by any rectified current therein, and means for impressing the direct voltage developed thereacross on said auxiliary electrode, whereby the translation efficiency of the system is reduced when the instantaneous amplitude of the input current exceeds said predetermined value.

6. In a wave-signaling system, a signal-translating stage having a signal input circuit normally subject to desired signals having a wide range of amplitudes and to disturbing electrical transients and an output circuit, and means for substantially suppressing said electrical transients from the output of the system comprising a vacuum tube included in said signal-translating stage and provided with a control electrode, said tube being of a type effective substantially to cut off the transmission of signals upon the biasing of its control electrode in excess of a critical

value, means responsive to the amplitude of the desired signal input to said stage for maintaining the maximum amplitude thereof near and below the predetermined critical value, and means for increasing the bias beyond said critical value upon the occurrence of an electrical transient at said input circuit.

7. In a wave-signaling system, a signal-translating stage having a signal input circuit normally subject to disturbing electrical transients and an output circuit, means for controlling the amplitude of the desired signal input thereto to maintain the maximum amplitude thereof near and below a predetermined critical value, said signal-translating stage being normally efficient in the translation of currents from said input circuit to said output circuit, full-wave rectifier means for deriving from said input circuit a biasing voltage dependent upon the instantaneous amplitude of currents therein, and means for reducing the efficiency of said translating stage only for biasing voltages corresponding to input currents exceeding said predetermined value, whereby said reduction is effected substantially instantaneously irrespective of polarity of said transient or said signal.

8. In a wave-signaling system, an input circuit, an output circuit, a pair of vacuum tubes each having a plurality of electrodes including input and output electrodes interconnected with said input and output circuits, respectively, to form a push-pull signal-translating stage, said translating stage including means coupled to said input circuit for deriving therefrom a biasing voltage dependent upon the instantaneous amplitude of the currents therein, and means for applying said biasing voltage with like polarity upon corresponding electrodes of said pair of tubes whereby the efficiency of said translating stage is reduced only for control voltages corresponding to input currents exceeding a predetermined amplitude and whereby disturbing impulses due to the sudden interruption of the space currents of said tubes are balanced out.

9. In a signal-modulated carrier wave receiving system, means for selectively admitting and amplifying desired signal waves, means for detecting said amplified signal waves, a signal-reproducing device, a signal-translating stage interconnecting said detecting means and said device, means for controlling the amplification of said amplifying means in inverse relation to the average intensity of the received carrier signal waves to maintain the maximum amplitude of the desired signal input to said translating stage near and below a predetermined critical value, and means responsive to the instantaneous amplitude of the total current in the input circuit of said signal-translating stage for suppressing the translation of all currents through said signal-translating stage only when the instantaneous amplitude of the input current thereto exceeds said predetermined value.

10. In a wave-signaling system including a signal-translating stage having input and output circuits, the method of receiving and translating desired signals having a wide range of amplitudes while suppressing disturbing electrical transients associated with said signals, which comprises variably amplifying the received signals and transients to raise any average amplitude of the desired signal to the same predetermined level, normally translating said amplified signals from said input circuit to said output circuit at constant efficiency and substantially sup-

- pressing the translation of all signals and transients from said input circuit to said output circuit when the instantaneous amplitude of combined signals and transients exceeds said predetermined level.
11. The method of receiving signal-modulated carrier waves while suppressing disturbing electrical transients associated therewith which comprises amplifying the received signal waves and transients, detecting said amplified signal waves to derive therefrom audio-frequency currents and a biasing voltage proportional to the average intensity of the received carrier wave, controlling said amplification in accordance with the magnitude of said biasing voltage to maintain the average amplitude of said audio-frequency currents substantially constant, amplifying said audio-frequency currents, deriving from said signal waves and transients a biasing voltage dependent upon the instantaneous value of said audio-frequency currents, and reducing the amplification in one of said amplifying steps substantially to zero for values of said last-mentioned biasing voltage corresponding to instantaneous amplitudes of said audio-frequency currents substantially exceeding said constant amplitude.
12. In a wave-signaling system, an input circuit, an output circuit, a pentode vacuum tube amplifier, said input circuit being connected to the suppressor grid of said tube, the anode and screen grid of said tube being connected in push-pull relation to said output circuit, means coupled to said input circuit for deriving therefrom a biasing voltage dependent upon the instantaneous amplitude of the currents therein, and means for applying said biasing voltage to the signal grid for reducing the efficiency of said translating stage only for biasing voltages corresponding to input currents exceeding a predetermined amplitude.
13. In a wave-signaling system, an input circuit, an output circuit, a pentode vacuum tube amplifier, said input circuit being connected to the suppressor grid of said tube, the anode and screen grid of said tube being connected in push-pull relation to said output circuit, means for equalizing the currents in the anode and screen grid circuits, auxiliary rectifier means coupled to said input circuit and having a time constant such that it follows substantially instantaneous variations in amplitude of the input current, and means for applying the output of said rectifier means as a bias to the signal grid of said tube for reducing the efficiency of said translating stage only for biasing voltages corresponding to input currents exceeding a predetermined amplitude.
14. A wave-signaling system, comprising a plurality of cascade-connected signal-translating stages each including input and output circuits, the first of said input circuits being normally subject to the desired signals having a wide range of amplitudes and to disturbing electrical transients, one of said stages other than the first comprising a vacuum tube having a plurality of electrodes including input and output electrodes coupled respectively to its associated input and output circuits, said tube being of a type effective substantially to cut off the transmission of signals upon the biasing of one of said electrodes in excess of a critical value, means responsive to the desired signal input to the system for maintaining the signal input to said one of said stages substantially constant, and means including full wave rectifier means coupled to the input circuit of one of said stages other than those following said one of said stages and responsive to the instantaneous amplitude of the total input current in the associated input circuit for normally biasing said one of said electrodes near said critical value and for increasing the bias thereof beyond said critical value upon the occurrence of an electrical transient in said system.
15. In a wave-signaling system, a signal-translating stage comprising input and output circuits and a vacuum tube having a plurality of electrodes including input and output electrodes coupled respectively to said input and output circuits, said tube being of a type effective substantially to cut off the translation of signals upon the biasing of one of said electrodes in excess of a critical value, impedance means comprising a parallel-connected resistor and capacitor connected to impress a bias voltage on said one of said electrodes, and means including a full wave rectifier coupled to said input circuit for developing a bias voltage across said impedance means variable with the instantaneous amplitude of the total current in said input circuit and which exceeds said critical value upon the occurrence of an electrical transient in said input circuit.
16. Method of reducing the effects of parasitic disturbances in a signaling system, including a circuit the conductivity of which depends upon the maintenance of an electron stream between elements in said system, which comprises impressing static affected signal waves upon said system, continuously rectifying the components of all amplitudes of a portion of said waves, and utilizing the rectified components thereof to concomitantly vary the conductivity of said circuit responsive to the receipt of waves of a desired amplitude and to interrupt the conductivity of said circuit for periods corresponding substantially to the actual duration of parasitic components having an amplitude greater than a certain predetermined value.
17. In a signaling system, the combination with a source of signal energy, a circuit the conductivity of which depends upon the maintenance of an electron stream between elements in said circuit and means for impressing signal energy from said source upon said circuit, of means for instantaneously controlling said electron stream in accordance with the amplitude of the energy impressed upon said circuit from said source, said means comprising a non-signal bearing electrode in the path of said stream, a device connected between said source and said circuit for converting a portion of said energy of all amplitudes into a potential capable of increasing the conductivity of said electron stream in response to signal intensities below a predetermined maximum, and into a potential capable of interrupting the conductivity of said electron stream in response to intensities above said maximum, and a conductive connection for said potentials from said device to said non-signal bearing electrode.
18. In a signaling system, a normally operative electronic repeater, means for impressing static affected bearing waves upon said repeater, means for rectifying at least a portion of all of said waves, and means responsive to rectified static components of said waves of an amplitude greater than a predetermined value for disabling said repeater for periods corresponding substantially to the actual duration of said components.
19. Method of reducing the effects of parasitic disturbances in a signaling system, including a normally operative electronic repeater, which

- comprises impressing static affected bearing waves upon said repeater, simultaneously and continuously rectifying the components of all amplitudes of a portion of said waves and utilizing the rectified components thereof to disable said repeater for periods corresponding substantially to the actual duration of parasitic components having an amplitude greater than a certain predetermined value.
20. In a signaling system, the combination with a source of signal energy, a translating circuit the conductivity of which depends upon the maintenance of an electron stream between elements in said circuit and means for impressing signal energy from said source upon said circuit, of means for interrupting said electron stream when the energy impressed upon said circuit from said source exceeds a predetermined intensity, said means comprising a non-signal bearing electrode in the path of said stream, a device connected between said source and said circuit for converting a portion of said energy of all amplitudes into a potential proportional to said energy, said potential being capable of interrupting said electron stream when said energy exceeds a predetermined value and a conductive connection for said potential from said converter to said non-signal bearing electrode, said device for converting a portion of said energy into a potential proportional to said energy being independent of the operation or the non-operation of said translating circuit.
21. In a signaling system, a normally operative electronic repeater, means for impressing static affected bearing waves upon said repeater, means for rectifying a portion of all of said waves, and means responsive to rectified parasitic components of said waves of an amplitude greater than a certain predetermined value for disabling said repeater for periods corresponding substantially to the actual duration of said components.
22. In a signaling system, a thermionic tube having at least two grids disposed between a cathode and an anode, a signal input circuit connected between the cathode and that one of the two grids remote from said cathode, means for rectifying the components of all amplitudes of a portion of the input circuit energy and means for continuously impressing upon the grid adjacent to the cathode a biasing potential proportional to the input circuit energy and of such a value as to substantially block the flow of electrons between said cathode and said anode only at such times as the input circuit energy exceeds a certain predetermined value.
23. Method of reducing the effects of static disturbances in a signaling system, including a control tube the conductivity of which depends upon the maintenance of an electron stream between elements of said tube, which comprises impressing static affected bearing waves upon said system, continuously rectifying the components of all amplitudes of at least a portion of said waves, and utilizing the rectified components thereof to concomitantly vary the conductivity of said control tube responsive to the receipt of waves of a desired amplitude and to interrupt the conductivity of said control tube for periods corresponding substantially to the actual duration of components having amplitude greater than a predetermined value.
24. A method of reducing the effects of static disturbances in a signaling system that includes a controlled tube whereof the conductivity depends upon the maintenance of an electron stream between elements of said tube, which comprises continuously rectifying, independently of a constant applied voltage, all amplitudes of at least a portion of the energy being transmitted through the system, applying said rectified energy to produce a voltage drop that is linearly proportional to the amplitude of said energy before rectification, and applying said voltage drop to the electron stream in said tube to interrupt the conductivity of said tube for periods corresponding substantially to the duration of components of said alternating current having amplitude greater than a predetermined value.
25. A method of reducing the effects of static disturbances in a signaling system that includes a controlled tube whereof the conductivity depends upon the maintenance of an electron stream between elements of said tube, which comprises continuously deriving a rectified current immediately from all the components of at least a half-wave of an alternating current, said rectified current thus having characteristics identical with the utilized portion of said alternating current, applying said rectified current to produce a drop in voltage that is directly proportional to the amplitude of said alternating current, and applying said voltage drop to the electron stream in said tube to interrupt the conductivity of said tube for periods corresponding substantially to the duration of components of said alternating current having amplitude greater than a predetermined value.

CERTIFICATE OF CORRECTION.

Patent No. 2,152,470.

March 28, 1939.

JOHN F. FARRINGTON.

It is hereby certified that error appears in the printed specification of the above numbered patent requiring correction as follows: Page 2, second column, line 42, for "Figs." read Fig.; page 3, second column, line 39, for the word "electrodes" read electrode; page 6, second column, line 66; page 7, first column, lines 1 and 35; and second column, line 6, claims 18, 19, 21, and 23 respectively, for "bearing" read signal; and that the said Letters Patent should be read with this correction therein that the same may conform to the record of the case in the Patent Office.

Signed and sealed this 6th day of June, A. D. 1939.
